POWER UNIT AND BASE FRAME FOR WASHING MACHINES

Walter Bones, Minneapolis, Minn., assignor to
 The Maytag Company, Newton, Iowa, a corporation of Delaware

Application September 10, 1936, Serial No. 100,073

4 Claims. (CL. 68—22)

The present invention relates to washing machines and more particularly to a novel power unit and base frame construction.

Among the objects of the present invention is to provide a combined power unit and base frame so constructed and arranged as to facilitate assembly and repair of the driving mechanism of a washing machine.

A further object is to provide a power unit and base frame which may be readily attached to or detached from the machine so as to facilitate servicing of the operating structure and make the parts more accessible for repair or replacement, as well as provide a standardized attachment.

A further object is to provide a novel power unit located below the base frame and leg supports of a washing machine, with the motor or engine mounted on and positioned above the base frame. In this construction the base frame which spans and supports the legs and forms a bracing reinforcement for the machine, provides the cover for the housing or casing enclosing and concealing the agitator and wringer drive mechanism.

Another object of the invention is to provide a novel construction and arrangement of power unit for a washing machine in which this unit is so mounted as to place no strain on the tub and supporting legs when the machine is being operated. By mounting the motor or engine in a manner as disclosed, there is less vibration and strain than in the prior arrangements and methods of mounting the drive mechanism and power plant. This provides for a longer life and less repair and servicing of the power unit.

Another object of the present invention is to provide a power unit and base frame for a washing machine in which these parts are located close to the floor in a manner to better balance the machine.

A still further object is to provide a novel drive mechanism for the agitator and wringer shaft of a washing machine. In the preferred construction and arrangement, the drive mechanism for the agitator and wringer is located within a housing mounted below the base frame and supported thereby.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illus-

trated in the accompanying drawings, and while I have shown therein a preferred embodiment, it is to be understood that the same is susceptible of modification and change, and comprehends other details, arrangements of parts, features and constructions without departing from the spirit of the invention.

In the drawings:

Fig. 1 is a view in side elevation of a washing machine provided with the novel power unit. 10

Fig. 2 is a plan view of the power unit with the base frame broken away to more clearly disclose the drive mechanism.

Fig. 3 is a view in vertical cross section of the power unit and base frame taken on the irregular line 3—3 of Fig. 2. 15

Fig. 4 is a view in vertical cross section of the base frame and power unit taken on the irregular line 4—4 of Fig. 2.

Referring more particularly to the disclosure in the drawings, the novel invention is embodied in a tub 1 having supporting legs 2. This tub and the support therefor may be of substantially square or round configuration in horizontal cross section, with an agitator 3 mounted therein upon a vertical drive shaft 4 extending through the bottom of the tub. Mounted at one side of the tub is a wringer drive shaft 5 adapted to operate a wringer 6 through a drive head 7. This wringer is preferably of the well-known swinging type provided with means for locking it in any desired position. 20

Mounted below the tub is a base frame 8 having outwardly projecting arms 9, each formed with a socket 10 for the reception of a leg. A set screw 11 is preferably provided for anchoring the frame to the leg at the desired position and level. This frame is also provided with an arm 12 of greater size than the arms 9, the purpose of which will be later more fully explained. 35

Projecting through the approximate center of this base frame is a stub shaft 13 having its upper end 14 encased in a bushing 15, bearing sleeve 16 and an oil seal 17 preferably formed of cork or the like. A flexible connector or coupling 18 is adapted to receive the lower end of the agitator drive shaft 4 and the outer end of the stub shaft 13, with pins or the like 19 for connecting the coupling to these shafts. This coupling accommodates any misalignment that may exist between the stub shaft and agitator drive shaft. 45

The base frame 8 serves as a cover and top closure for a gear casing 20 housing the drive mechanism or power unit for the agitator and wringer, and a support for the motor or other

- engine 21, as well as serving as a bracing reinforcement for the washing machine. The motor 21 is suitably bolted or fixed upon the top of this base frame and is provided with a pulley 22 adapted to drive by means of a belt or the like A, a pulley 23 upon the outer end of a drive shaft 24 extending into the casing or housing 20, and bearing in opposite projections or bosses 25 and 26 of the housing.
- 10   Mounted upon the shaft 24 is a worm 27 meshing with and continuously driving a worm wheel 28 adapted to rotate on a stud pin 29 fixedly mounted in the boss 30 in the base 31 of the gear casing. The worm wheel is hollowed out to receive an annular clutch disc 32 having a tapered clutching surface or face 33 adapted to be moved into and out of clutching engagement with a complementary clutch face 34 formed on the inner circumference of the rim of the worm gear.
- 15   Normally this clutch disc 32 is forced upwardly and held out of clutching engagement by a spring washer or the like 35, seating against the hub 36 of the clutch disc. In order to bring this disc into frictional clutching engagement with the worm wheel, the invention comprehends a washer or plate 37 placed over the upper or outer surface of the clutch hub 36 and adapted to be pulled downwardly by a bolt or the like 38 with its shank 39 passing through an opening in the stud pin 29 and sealed by means of an oil seal 40.

The lower end of the bolt 38 is connected to a shifter arm 41, by the nuts 42. This arm is adapted to be depressed by any suitable mechanism located on an accessible part of the machine. As disclosed in Fig. 1, this mechanism may comprise a toggle 43, pivoted upon a projection 44 suitably located on the exterior of the gear housing, and connected to a rod or lever 45 having a handle 46, which when depressed, forces the outer end of the arm 41 downwardly and this arm pivoting about its inner end 47 on the boss 30, will lower the bolt 38 and the clutch disc 32 into clutching engagement with the worm wheel. It will be apparent that when the toggle 43 is in the position shown in Fig. 1, the spring washer 35 will maintain the clutch disc 32 out of clutching position, but when the lever 45 is depressed so that the lower end of the toggle is in a substantially vertical position, the shifter arm or blade 41 is depressed to clutch the parts and this clutching engagement will be maintained until the lever is again raised.

50   Mounted on the clutch disc 32 is a crank pin or bearing 48 connected to a connecting rod 49. This rod is in turn connected to and oscillates a connecting arm 50 pivotally mounted upon a stud pin or shaft 51 having a bearing in the boss 52, the arcuate end 53 of the arm being pivotally mounted or hinged to a shuttle knuckle 54 that slides in the guideway 55 of an arm 56 suitably pinned or keyed to the stub shaft 13 to be oscillated.

55   Due to the peculiar arrangement of pivoting points of the connecting arms and rod with respect to each other and the shuttle effect on the arm 56, and due to the dead centers of the crank movement, the stub shaft 13 which oscillates the agitator 3 through the agitator drive shaft 4, accelerates and decelerates the movement of the agitator drive shaft in doubly increased and decreased ratios which transmits to the agitator corresponding whipping alternations or oscillations.

60   Mounted on the underside of the worm wheel 28 is a spur gear 57 meshing with and driving a train

of gears 58, 59, 60 and 61, the latter being mounted on a stub shaft 62 and driving the wringer drive shaft 5, through a flexible coupling 63. This coupling or connector accommodates any misalignment of the stub shaft 62 and wringer drive shaft 5 when the base frame and power unit are assembled on the machine. A sleeve 64 preferably encloses the wringer shaft.

65   It will be readily appreciated that the base frame which forms a bracing reinforcement for the machine as well as a cover and support for the power unit or drive mechanism for the agitator and wringer, and a support for the motor or engine, may be made of a stamping that closely hugs and protects the gear housing or casing and gives a neat appearance to the unit. All of the drive mechanism is thus enclosed and hid under this frame.

70   The present construction permits a standardized power unit which may be assembled as a complete, enclosed unit and so removed for servicing or replacement.

75   If desired, a hood or enclosure 65 may be provided for the motor and a hood or enclosure 66 for the belt drive. This protects the structure against water being spilled thereon and eliminates danger to the operator, as well as lends to the appearance of the machine.

80   Having thus disclosed the invention,

I claim:

1. A combined base frame and power unit for a washing machine having a tub and supporting legs, comprising a frame member adapted to span the legs adjacent their ends, a socket formed at each extremity of the frame for receiving a leg and providing for adjustment of the frame upon the legs, means for anchoring the frame in adjusted position upon the legs, a drive mechanism carried by the underside of the frame, and a housing below and secured to the underside of the frame and providing, with the frame, a complete enclosure for protecting and concealing the drive mechanism.

2. A readily detachable power unit and base frame constructed and arranged as to standardize construction and facilitate assembly and servicing of the operating mechanism of a washing machine having a tub and supporting legs, comprising a supporting frame having means shaped to surround the supporting legs and adjustably mounted thereon below and spaced from the bottom of the tub, drive mechanism for operating the machine located adjacent the floor and below the frame and supported therefrom and a housing below and secured to the underside of the frame and providing, with the frame, a complete enclosure for protecting and concealing the drive mechanism.

3. A readily detachable and combined frame and power unit for a washing machine comprising a frame member adapted to span the legs, a socket provided at each extremity of the frame for receiving a leg and providing for adjustment of the frame upon the legs, adjustable anchoring means for securing the frame in adjusted position upon the legs, a drive mechanism located below the frame, a casing suspended from the underside of the frame and providing an enclosure for mounting, protecting and concealing the drive mechanism and a motor mounted on the upper surface of the frame.

4. A readily detachable and combined frame and power unit for a washing machine for operating the agitator and wringer drive shafts, comprising a frame detachably and adjustably mounted

ed on the supporting legs for the machine, a power unit carried by the underside of the frame for operating the agitator and wringer drive shafts and including power actuated stub shafts extending through and to a position above the frame, means shaped to surround the legs, and means for anchoring the frame on the said legs whereby the frame is directly supported from the legs, the said stub shafts having detachable shaft couplings 5 for connecting the same to the agitator and

wringer shafts, and a housing suspended from the underside of the frame and providing, with the frame, an enclosure for mounting, protecting and concealing the drive mechanism, the frame and power unit being so constructed and arranged that the weight thereof is located close to the floor or supporting surface for the machine and thereby balancing and stabilizing the machine. 10

WALTER BONES. 10
